UNITED STATES PATENT OFFICE

116,552

DESIGN FOR AN AUTOMATON ADVERTISING AND MERCHANDISING DEVICE

Frank L. Dale, New York, N. Y., assignor to Mechanical Man, Inc., New York, N. Y., a corporation of New York

Application January 28, 1939, Serial No. 82,648

Term of patent 7 years

To all whom it may concern:

Be it known that I, Frank L. Dale, a citizen of the United States, residing at 5 Riverside Drive, in the city, county, and State of New York, have invented a new, original, and ornamental Design for an Automaton Advertising and Merchandising Device, of which the following is a specification, reference being had to the accompanying drawing, forming part thereof.

The figure is a front perspective view of an automaton advertising and merchandising device, showing my new design.

I claim:

The ornamental design for an automaton advertising and merchandising device, as shown.

FRANK L. DALE,
